Primary Examiner — Philip S Hyder(74) *Attorney, Agent, or Firm* — The Belles Group, P.C.(57) **CLAIM**

The ornamental design for a hinged joint for a tool handle, as shown and described.

DESCRIPTION

FIG. 1 is a top perspective view of a hinged joint for a tool handle according to new design;

FIG. 2 is a bottom perspective view thereof;

FIG. 3 is a first side view thereof;

FIG. 4 is a second side view thereof opposite the first side;

FIG. 5 is a third side view thereof;

FIG. 6 is a fourth side view opposite the third side view;

FIG. 7 is a top view thereof; and,

FIG. 8 is a bottom view thereof.

The broken line showing of the tool handle is provided for purposes of environment and forms no part of the claimed design.
